UNITED STATES PATENT OFFICE.

EDWARD F. KUNATH, OF JERSEY CITY, NEW JERSEY, ASSIGNOR, BY MESNE ASSIGNMENTS, TO UNDERWOOD TYPEWRITER COMPANY, OF NEW YORK, N. Y., A CORPORATION OF NEW JERSEY.

TOOL FOR APPLYING TYPE TO TYPE-BARS OF WRITING-MACHINES.

SPECIFICATION forming part of Letters Patent No. 734,719, dated July 28, 1903.

Application filed January 17, 1903, Serial No. 139,398. (No model.)

To all whom it may concern:

Be it known that I, EDWARD F. KUNATH, a citizen of the United States, residing at Jersey City Heights, county of Hudson, State of New Jersey, have invented certain new and useful Improvements in Tools for Applying Type to Type-Bars of Writing-Machines, of which the following is a specification.

My invention relates to an implement to be used for the purpose of properly applying type to the type-bars of writing-machines. It is well known that as usually made type-writing machines comprise a set of type-bars having their type-carrying ends bent at different angles to the body of the type-bar, according to the position of the respective type-bars in the machine. It will be obvious that if the type has to be renewed it is of great importance to have the new type secured in exactly the same position as the old one, since otherwise the required alinement of the type will be lost and a defective impression would be the result.

To provide simple and efficient means for the above-indicated purpose, I have devised a tool, which will now be described in detail with reference to the accompanying drawings, and the novel features of my invention will then be pointed out in the appended claims.

Figure 1 is a plan of my improved tool with a type-bar thereon. Fig. 2 is a plan with the type-bar removed. Fig. 3 is a sectional elevation on line 3 3 of Fig. 1. Fig. 4 is a cross-section on line 4 4 of Fig. 3, and Fig. 5 shows a slightly-different form of my tool in side elevation.

Briefly described, my invention comprises a handle-section or body-section adapted to pivotally receive the type-bar, an anvil-carrying section pivotally connected with said handle-section, and an adjustable anvil carried by the anvil-section.

In the form of construction illustrated by Figs. 1, 2, 3, and 4 the body or handle A is provided at one end with a slot A', across which extends a pin A², adapted to form a pivot for the type-bar B. This bar, as shown in Fig. 3, engages the pin A² in the same manner in which it is engaged with the type-bar pivot of a type-writing machine. A spring

C is secured to the handle A and extends into the slot A' to engage the toe B' of the type-bar, so as to throw the latter down into the position shown in Fig. 3. The forward or free end of the type-bar carries the type-block D, provided with type D'. The connection of the type-block D with the type-bar B is generally effected by means of solder. The handle portion A is slightly shorter than the type-bar, so that the type-carrying end of the latter projects beyond the handle. At the end of the handle opposite to that at which the pivot A² is arranged the anvil-carrying section E is pivotally connected with the handle, as indicated at E', the axes A² and E' being at right angles to each other, so that the plane in which the anvil-carrier E swings will be at a right angle to the path of the type-bar. At the end adjacent to the handle the anvil-carrier is provided with a slot E², adapted to receive the bent portion B² of the type-bar adjacent to the type-block D. The anvil-carrier has loosely supported thereon an anvil F, adapted to assume different positions, and suitable mechanism is also provided for securing the anvil in the adjusted position. In the particular construction shown the anvil-carrier is slotted lengthwise and the free ends of the arms or fork members so formed are connected by a screw G, by the turning of which the stem F' of the anvil may be clamped between the fork members and held immovable. The fork members are beveled on their inner surfaces, as shown in Fig. 4, and the stem F' preferably is widened somewhat at the bottom, so as to prevent an accidental removal of the anvil from its carrier. The upper surface of the anvil, which extends over the fork members of the carrier, is substantially smooth; but the lower surface of the anvil proper is rounded from front to rear, as shown in Fig. 3, thus enabling the anvil to rock forward or rearward when the screw G is sufficiently loose. It is also preferable to taper the stem F' from its central portion toward both ends. At the end adjacent to the handle the anvil F' is provided with a transverse ridge or stop F², adapted to be engaged by the type D'. The handle A is further provided with an

adjustable gage H, adapted to engage the type-bar B, said gage being preferably in the nature of a screw.

When my tool is to be used in connection with type-bars which carry their pivot permanently, as illustrated in Fig. 5, I slightly vary the construction of the handle by providing it with two angular slots A³, adapted to receive the pivot B³ of the type-bar B⁴.

10 In other respects, however, the construction may be the same as hereinbefore described.

The tool is used as follows: The type-bar is inserted in the slot A' and pivotally connected with the handle A in practically the same manner in which it is pivotally supported on the type-writing machine. The anvil-carrier E' is then, if necessary, turned to one side or the other, so that the projection B² of the type-bar will enter the slot E².
 15 The dotted lines in Fig. 2 indicate the range of adjustment of the anvil-carrier E; but it will be understood that a greater or smaller range of adjustment may be employed. The screw G is supposed to be loose, so that when the type D' is brought in engagement with the upper surface of the anvil by the spring C the anvil will spontaneously take a position in which it will engage the types evenly. It will be seen that the anvil may slide forward and rearward—that is, toward and from the pivot E'—and may also rock lengthwise, so as to raise one end more than the other. The anvil is pulled out until the type D' engages the ridge or shoulder F². After the 20 anvil has been adjusted as described the screw G is tightened, so as to hold the anvil in its adjusted position. The projection B² of the type-bar serves to keep the anvil-carrier at the proper angle relatively to the handle. The screw E', however, may be employed as a clamp for this purpose, and this is particularly the case when the type-bar has no projection, such as B², adjacent to the type-block D. (See Fig. 5.) The type-block may 25 now be removed and another type-block substituted for it, and as this new type-block will rest on the anvil F, which has been adjusted to the position of the old type-block, it follows that the new type-block will be secured 30 in exactly the same position as the old one. When the old type-block has been removed, there would be nothing to keep the type-bar from a downward movement under the influence of the spring C, and it might happen 35 that the type-bar and the new type-block would not be connected properly. To prevent this, I have provided the gage or screw H, which is so adjusted as to keep the type-bar in its proper position even after the removal of the type-block.

My improved tool, as above described, enables repairs to be made to the type-bars by the substitution of new type-blocks, while preserving the proper position of the type-face.

40 It will be understood that the type-bars of a type-writing machine differ from each other as to the angle between the body of the type-

bar and that end which carries the type-block. Some of the type-bars are perfectly straight, like the one shown in Fig. 1. Most 70 type-bars, however, have a bend at their free end, and this bend varies from type-bar to type-bar. When provision is made for locking the anvil-carrier to the handle A, the tool could be used for fitting new type-levers with 75 proper type.

I desire it to be understood that I do not restrict myself to the specific construction shown.

What I claim as new, and desire to secure 80 by Letters Patent, is—

1. A tool for applying type to the type-bars of type-writing machines, comprising a handle having means for connecting it with a type-bar, an anvil-carrier movably connected with 85 said handle, and an anvil mounted on said carrier and provided with a shoulder adapted for engagement by the type.

2. A tool for applying type to the type-bars of type-writing machines, comprising a handle adapted to support the type-bar, an anvil-carrier pivoted to said handle, an anvil loosely carried by said carrier, and means for locking the anvil to the carrier.

3. A tool for applying type to the type-bars 95 of type-writing machines, said tool comprising a handle having means for pivotally connecting a type-bar therewith, an anvil-carrier pivoted to the handle to swing in a plane at right angles to the path of the type-bar, an 100 anvil loosely mounted on said carrier, and means for locking the anvil to the carrier.

4. A tool for applying type to the type-bars of type-writing machines, said tool comprising a handle adapted for connection with a 105 type-bar, an anvil-carrier adjustably connected with said handle, an anvil loosely mounted on said carrier, and means for locking the anvil to the carrier.

5. A tool for applying type to the type-bars 110 of type-writing machines, said tool comprising a handle having means for connecting it with a type-bar, an anvil-carrier pivoted to the handle and having spaced members movable toward and from each other, an anvil 115 loosely held between said members, and means for pressing said members together to hold the anvil in place.

6. A tool for applying type to the type-bars of type-writing machines, said tool comprising a handle having means for receiving type-bars, an anvil-carrier pivoted to the handle, an anvil adjustable toward and from the pivot of the carrier, and means for locking the anvil in its adjusted position.

7. A tool for applying type to the type-bars of type-writing machines, comprising a handle having means for connecting it with a type-bar, an anvil-carrier adjustably connected with said handle, an anvil mounted on said carrier and movable toward and from the handle, and also capable of a rocking movement, and means for locking the anvil in its adjusted position.

8. A tool for applying type to the type-bars of type-writing machines, said tool comprising a handle having means for connecting a type-bar therewith, an anvil-carrier adjustably connected with said handle, and an anvil mounted on said carrier and capable of a rocking movement, and means for locking the anvil in its adjusted position.
9. A tool for applying type to the type-bars of type-writing machines, comprising a handle having means for connecting a type-bar therewith, an anvil-carrier pivotally connected with the handle and provided with a slot adapted to be engaged by the type-bar, to hold the anvil-carrier in its adjusted position, and an anvil mounted on said carrier.
10. A tool for applying type to the type-bars of type-writing machines, comprising a handle having means for connecting a type-bar therewith, an anvil movably connected with

the handle and adapted to engage the type of the type-bar, and a gage adjustably carried by the handle and arranged to hold the type-bar body in its adjusted position.

11. A tool for applying type to the type-bars of type-writing machines, said tool comprising a handle having means for receiving the pivot portion of a type-bar, and a spring for engaging said type-bar and for forcing it toward the handle, and an anvil movably connected with the handle and adapted to engage the type on the type-bar.

In testimony whereof I have hereunto set my hand in the presence of two subscribing witnesses.

EDWARD F. KUNATH.
